CLAIM

The ornamental designs for a dental treatment instrument, as shown and described.

DESCRIPTION

FIG. 1 is a front, right, top side perspective view of a dental treatment instrument in accordance with an embodiment of the present design.

FIG. 2 is a rear, left, bottom side perspective view of the dental treatment instrument shown in FIG. 1.

FIG. 3 is a right side plan view of the dental treatment instrument shown in FIG. 1.

FIG. 4 is a left side plan view of the dental treatment instrument shown in FIG. 1.

FIG. 5 is a top side plan view of the dental treatment instrument shown in FIG. 1.

FIG. 6 is a bottom side plan view of the dental treatment instrument shown in FIG. 1.

FIG. 7 is a rear view of the dental treatment instrument shown in FIG. 1; and,

FIG. 8 is a front view of the dental treatment instrument shown in FIG. 1.

In the drawings, the broken lines depict environmental subject matter only and form no part of the claimed design.

1 Claim, 6 Drawing Sheets
